UNITED STATES PATENT OFFICE

2,660,037

REFRIGERATOR CONSTRUCTION

La Mar S. Cooper, Cedar Rapids, Iowa, assignor
to Amana Refrigeration, Inc., Cedar Rapids,
Iowa, a corporation of Iowa

Application November 13, 1950, Serial No. 195,231

2 Claims. (Cl. 62—116)

1

The present invention relates to refrigerator structures. The invention is illustrated herein as applied to a frozen food storage cabinet, but it is applicable to all types of refrigerating machines whether of the frozen food type or the higher temperature refrigerating type.

An object of the invention is the provision of a refrigerator cabinet having a cavity or recess in its outer surface for mounting the motor-compressor unit of the refrigerating mechanism, whereby the exterior dimensions of the refrigerator need not be enlarged because of the unit, and the interior storage compartment need not be reduced in size, and in which insulation having a lower K factor than normal is interposed in that portion of the construction between the cavity and the interior compartment.

Another object of the invention is the provision of a refrigerator having a novel mounting of the condenser which forms part of the refrigerating apparatus.

More specifically, an object of the invention is the provision of a refrigerator having a condenser mounted in a novel manner and in such a way as to facilitate the passage of air over the condenser.

Another object of the invention is the provision of a refrigerator having a condenser coil mounted on the back wall of the refrigerator and in which the condenser has horizontally arranged runs of tubing mounted on a louver plate in which the louver plate is disposed at an angle to the vertical whereby upwardly flowing currents of air flow through the louver plate and effectively cool the condenser.

Still another object is the provision of a refrigerator having a condenser of the character just referred to, and having bumper means for engaging the wall of the room in which the refrigerator is placed for spacing the refrigerator from that wall to enable the currents of the air to readily flow upwardly around the runs of the condenser coil.

A further object of the invention is the provision of novel supporting means for the motor-compressor unit of the refrigerating mechanism.

With these and other objects in view, my invention consists in the construction, arrangement and combination of the various parts of my refrigeration construction, whereby the objects contemplated are attained, as hereinafter more fully set forth, pointed out in my claims and illustrated in the accompanying drawings, wherein

Figure 1 is a side view of a freezer employing

the present invention showing a portion of the freezer in vertical section.

Figure 2 is a view from the rear of the freezer as viewed from the right of Figure 1.

5 Figure 3 is an enlarged sectional view of a portion of the freezer showing in detail the means for mounting the motor-compressor unit.

Figure 4 is a view from the right of Figure 3, but on a reduced scale relative to Figure 3.

10 Figure 5 is an enlarged detail view of a portion of the louver plate and condenser coil.

Figure 6 is a sectional view taken on line 6—6 of Figure 1.

15 Figure 7 is a detailed view of a portion of the mounting means for the motor-compressor unit.

Referring now in detail to the drawing, numeral 12 indicates a frozen food storage cabinet, as distinguished from what is commonly known as a domestic refrigerator primarily used for

20 storing unfrozen foods. Although the invention is shown applied to a frozen food storage cabinet, it will be understood that it is also readily applicable to any mechanical or absorption type of refrigerator.

25 Figure 12 includes a cabinet 14 having a plurality of vertical side walls, one of which, 16, is the rear wall, the other walls being indicated generally by the numeral 18. The cabinet also includes a bottom wall 20. The cabinet is open at 30 the top and is closed by a cover 22 hinged at 24 on brackets 26. The cabinet structure also includes foot members 27 with adjustable gliders 28.

The cabinet is made up of an outer case 29 which is preferably of sheet metal and an inner

35 liner 30 also of sheet metal. Insulation 32 is disposed between the outer case and liner, throughout the greater portion of the cabinet. The liner 30 defines a storage compartment of the freezer and this storage compartment is accessible

40 through the open top of the freezer. It will be understood that the cover 22 is also heat insulated.

A refrigerating mechanism is provided comprising a motor-compressor unit 34, an evaporator

45 36, and a condenser 38. The evaporator 36 includes tubing in thermal contact engagement with the liner 30 for the purpose of refrigerating the interior storage compartment. The parts of the refrigerating system are connected with suitable 50 tubing, with a pressure reducing device between the condenser 38 and evaporator 36, neither the tubing or the pressure reducing device being shown.

A recess or cavity 40 is formed in the cabinet 55 at the lower rear corner thereof. The outer case

29 includes a wall portion 42 disposed diagonally with respect to the rear wall and the bottom wall, which forms a recess which is inset with respect to the normal rectangular outline of the cabinet. The recess has an innermost surface 44 and end surfaces 46. The motor-compressor unit 34 is mounted in the cavity 40 for purposes that will be more fully explained later. Because of the diagonal disposition of the surface 44 of the cavity, that surface is relatively close to the lowermost corner of the liner 30 and the storage compartment, and in this reduced space, an excessive amount of heat would enter the storage compartment if the insulation, at this point, was of the same insulating characteristics as in the other parts of the cabinet.

Accordingly, I have provided a segment or portion of insulation indicated at 48 which is disposed between the surface 44 and the adjacent corner of the liner 30. This insulation 48 has a lower K factor than the remainder of the insulation 16. It is understood that the K factor is the coefficient of heat transfer, and insulation of a lower K factor has greater insulating qualities than insulation of a higher K factor. The portion of insulation 48 extends on opposite sides of the lower corner of storage compartment to an extent necessary to insure that the heat leakage into the cabinet at this point is substantially no greater than into other portions of the cabinet, even though the wall section is thinner. Insulation having a lower K factor is generally more expensive than insulation with a higher K factor, and it is desirable, therefore, to use as little of the lower K factor insulation as possible.

The motor-compressor unit 34 is mounted in a position wherein a substantial portion of the unit is disposed in the recess 40 so that the unit is positioned as much as possible within the outline contour of the cabinet. The length of the recess 40 is no greater than necessary to conveniently accommodate the unit 34. Figures 1 and 2 show to best advantage the positioning of the unit 34 in the cavity.

The motor-compressor unit 34 may be a conventional or standard unit having a shell in which the motor and the compressor (not shown) are enclosed. The shell has circular end members 50, on each of which is a mounting member indicated generally at 52 (Figure 3). Each mounting member 52 includes a pair of collar elements 54 and 56 which, when fitted together, form a collar or band encircling the end member. The element 56 includes flanges 58 and the element 54 includes radially extending portions 60 and upwardly extending portions 62.

The flanges 58 and portions 60 are in substantial register, having aligned holes through which bolts 64 are inserted. The bolts are provided with nuts for clamping the collar elements 54 and 56 tightly on the end members. The upper ends of the portions 62 are provided with notches 66, which as illustrated in Figure 7, are disposed on opposite edges of the portions 62, the notches on opposite edges being offset vertically and the notches in each element forming disconnected segments of a helical groove.

Other mounting members are indicated at 68. A pair of such members are provided, one for each of the mounting members on the motor-compressor unit. Each mounting member 68 includes a pair of straps having upper straight portions 70 which are fitted with their flat surfaces spot welded together, as indicated at 72.

Portions 70 are provided with vertically elongated slots 74 for receiving screws 76 for mounting the members. The outer case 29 in the rear wall 16 of the cabinet is provided with a plate 78 secured to the inner surface of the outer case. A heavy steel element 80 is mounted on the plate 78. The screws 76 are inserted through the slots 74 and threaded into tapped holes in the element 80 for mounting the members 68. Because of the elongated dimensions of the slots 74, the members 68 may be adjusted vertically within limits.

The straps making up the mounting members 68 diverge at their lower portions, as indicated at 82, and their lowermost ends extend substantially vertically, as indicated at 84. The lower ends 84, as viewed in Figure 8, are provided with notches 86, in each of its opposite edges, and these notches form disconnected segments of a helix, as described in connection with the notches 66.

The lower end portions 84 of the straps are disposed so as to register with respective ones of the upwardly extending elements 62 of the mounting members on the unit 34. Helical springs 88 are threaded into the notches 66 and 86, as shown in Figure 3. The springs 88 thus yieldably support the motor-compressor unit 34 from the cabinet, absorbing the vibrations of the unit. It will be observed that one portion of each of the mounting members 82 extend into the recess 40, so that the motor-compressor unit is disposed with a substantial portion thereof in the recess 40.

Mounted on the rear surface of the rear wall 16 is a louver plate indicated generally at 90, having horizontally extending elements 92 stamped therefrom. The louver plate 90 has portions 94 at the ends extending at right angles to the main surface of the plate, the extended edges being secured to the cabinet by any desired means. The main portion of the louver plate 90 as best shown in Figure 1, is inclined from the vertical, although adjacent the vertical. The louver elements 92 are stamped from the plate 90 in a direction opposite that from which the plane of the plate 90 is inclined from vertical. The plate 90 forms a duct with the wall of the refrigerator, the duct being open at the top, as best shown in Figure 6.

The condenser 38 is in the form of a coil having a plurality of horizontal runs 96. These runs 96 are preferably brazed onto the inner surface of respective louver elements 92.

As will be observed in Figure 1, the louver plate 90 and thus the condenser coil 38 are disposed in a plane that is inclined slightly from the vertical and it will be noted that the upper end of the plate and condenser is spaced a greater distance from the refrigerator cabinet than the lower end. Air currents are thus permitted to flow upwardly between the condenser 38 and the wall 106 which is a wall of the room in which the refrigerator cabinet is disposed. The air currents between the condenser 38 and the wall 106 flow through the spaces between the louver elements 92 and into the duct formed by the plate 90. The portion of air coming in contact with any one of the runs 96 does not normally come in contact with the other runs above that run. Fresh increments of air are applied to each of the runs 96 of the coil and thus dissipation of heat from the condenser 38 is most effective. The louver elements 92 are of substantial vertical dimension, whereby the air in passing over and coming in engagement with the louver elements 92 is of greater effect in dissipating the heat from the condenser coil 96, because of that

vertical dimension being substantially greater than the vertical dimension of the runs of the coil. Because of the inclination of the condenser, portions of the air between the condenser and the wall 106 rise substantially to the top of the condenser, whereby relatively cold air is directed into engagement with the uppermost runs 96 of the condenser coil, without having first passed over the lower runs 96. Thereby, all of the runs 96 are subjected individually to increments of cold air.

It will also be noted that the inclination of the louver elements 92, being opposite to the inclination of the plane of the condenser 38, is effective for baffling the air through spaces between the louver elements 92 and between the runs 96 of the condenser coil.

Bumper elements 108 are mounted in the mounting bracket 26 adjacent the upper end of the condenser 38. These bumper elements 108 are adapted to engage the wall 106 and space the cabinet from the wall 106 to provide the necessary space between the condenser 38 and the wall for the passage of air. It will be noted that the motor-compressor unit 34 is disposed within the limits defined by the innermost surface of the recess or cavity 40 and the outermost surface of the condenser 38. Thus the refrigerator may be positioned closely adjacent the wall 106 and it is not necessary to position the unit outside the general outline of the whole refrigerator cabinet. It is also not necessary to reduce the space of the storage compartment in order to position the unit within the outline of the cabinet. Furthermore the heat insulating effect of the insulation of the cabinet, including the reduced space between the cavity 40 and the interior storage space, is substantially uniform throughout the cabinet.

While I have shown a preferred embodiment of my invention, it will be understood, of course, that I do not wish to be limited thereto, since many modifications may be made, and I therefore contemplate by the claims appended hereto to cover any such modifications or substitutions of equivalents as fall within the true spirit and scope of my invention.

I claim:

1. In a refrigerator, a cabinet having an interior compartment to be cooled and refrigerating mechanism for cooling said compartment including a motor-compressor unit, a downwardly extending mounting member secured to said cabinet, an upwardly extending mounting member secured to said unit, the extended ends of

said mounting members having vertically spaced notches in each of opposite edges thereof, the notches in each mounting member forming disconnected segments of a helix, and a helical spring threaded in the notches of said mounting members, said spring being operative for yieldably supporting said unit.

2. In a refrigerator, a cabinet having side walls and a bottom wall, and an interior compartment to be cooled, said refrigerator also having refrigerating mechanism for cooling said compartment including a motor-compressor unit, and a condenser, said condenser being mounted on one of said side walls in generally vertically disposed position and in laterally spaced relation with respect to the wall, said one side wall having a cavity in its outer surface adjacent the bottom thereof, said unit being mounted with a substantial portion thereon disposed in said cavity, a mounting member secured to each end of said unit, each mounting means having a pair of laterally spaced, upwardly extending elements, a pair of upper mounting members secured to said one wall above said cavity and extending downwardly below the upper limit of the cavity, each upper mounting member having a pair of laterally spaced elements in substantial register with the respective elements of the mounting members on the unit, one element of each mounting member extending into said cavity, each of said elements having vertically spaced notches in each of opposite edges thereof, the notches of each element forming disconnected segments of a helix, and a helical spring threaded in the notches of each of the registered elements, whereby said springs yieldably support said unit in such position that a substantial portion thereof is disposed in said cavity and the unit is within the limits of the innermost surface of the cavity and the outermost surface of the condenser.

LA MAR S. COOPER.
